MATERNITY GIRDLE AND GARTER SUPPORTER

Paula Blatt, Cleveland, Ohio

Application March 7, 1955, Serial No. 492,686

6 Claims. (Cl. 128—535)

This invention is for an improved maternity girdle and garter-supporting means and is related to my co-pending application Serial No. 259,214, filed November 30, 1951, now Patent No. 2,710,486.

One object of my present invention is to provide a comparatively simple structure that is highly efficient and that can be manufactured and sold at a popular price.

Another particular object is to devise such a garment with an improved means of adjustable and detachable engagement about the waist of the wearer's body and also an improved adjustable means for attaching the garters directly to the garment.

Another object is to provide such a garment with an improved means for engaging the side portions of the hip regions of the wearer's body in a firm manner over an extended area so as to afford her a sensation of security and comfort throughout this region of her body and also to serve as a means of increasing the dependability of the garment in maintaining its proper position upon her body at all times.

Other objects will appear from the following description and claims when considered together with the accompanying drawing.

Fig. 1 is a front view illustrating the position of my present garment upon the body of the wearer;

Fig. 2 is a side elevation thereof;

Fig. 3 is a rear view thereof;

Fig. 4 is an enlarged view illustrating the adjustable and detachable connection at the rear of the garment.

Referring now to the accompanying drawing in detail, the single continuous longitudinally elastic strip 1 of uniform width throughout is adapted for engagement beneath the abdomen of the wearer's body and is adapted to extend thence upwardly and rearwardly over the hips of the wearer's body and about her waist including her sacroiliac region. At the rear part of this garment the strip 1 is provided with a readily detachable and adjustable means of connection between the ends thereof, as will be fully described.

The longitudinally elastic garter-supporting straps 2 and 3 have their upper ends attached to the strip 1 at such points as to locate these straps approximately along the front median line of the wearer's thigh in each instance so as to exert a straight-line tension along the thigh and thus support the garter G in proper position of engagement with the stocking without any danger of twisting the stocking. Other garter-supporting straps are attached to the strip 1 so as to extend down along the rear-side part of the thigh, in each instance, as indicated by reference numerals 4 and 5, respectively; and the straps 4 and 5 are adapted to extend in a vertical direction substantially parallel in each instance with the companion straps 2 and 3, respectively. Each of the straps 4 and 5 has direct supporting connection to a garter G which may engage the stocking at a point at the rear-side part of the wearer's thigh, as illustrated in the present drawing, so as to exert tension along a straight line and thus without any danger of twisting the stocking.

At the side of each thigh of the wearer's body I have provided a substantially triangular body of universally elastic lace 6 between the strip 1 and the straps 4 and 5. A longitudinally elastic strip 7 extends between the two straps 4 and 5 and along the bottom edge portion of each elastic body 6 and the inner lower edge portion of the abdomen-supporting part of the strip 1. In sewing the strips 1 and 7 together, this is done while this part of the outer strip 1 is in stretched condition so that, upon releasing the same after being sewed together, the contraction of the outer strip 1 will tend to produce an outward curved or arched form which will be more naturally adapted for engagement beneath the abdomen of the wearer's body. This manner of connection between these two overlying parts will result also in an upward and outward inclination of this part of the strip 1 so as to still more effectively afford a comfortable supporting engagement for the abdomen.

The fastening means between the ends of the strip 1 at the rear of the garment includes two duplicate old elements 10 and 11 of metal or other suitable rigid material. Each of these elements has an eye between the parallel portions 10a—10b and 11a—11b, and an integral hook portion 10c, 11c that is parallel to the side portions of the eye in each instance. The strip 1 from one side of the wearer's body has its end formed as a comparatively long loop 12 that is adapted for readily detachable engagement with the hook portions 10c of the element 10. The end portion of the strip 1 at the other side of the garment is extended from the inside of the element 11 outwardly through the eye thereof, thence inwardly through the space between the eye and the hook portion 11c of the element 11, thence past the inner side of the hook portion 11c and thence outwardly through the space between the hook and eye portions of the element 10 and thence inwardly through the eye thereof and back upon itself to the hook portion 11c of the element 11 where it has a small loop portion 13 releasably engaged over the hook portion 11c of the element 11. Then, by sliding the element 11 along the strip 1 which may be moved through the other element 10, the size may be adjusted as may be desired; and the larger loop 12 may be readily detached for removal of the garment from the body of the wearer. With this arrangement, I am enabled to utilize old fastening elements in a new and convenient manner for producing a readily releasable and adjustable form of connection in the present garment.

Also I utilize another of these old fastening elements in my present adjustable engagement for each of the garters G. Here also the fastening element has a loop or eye with its parallel portions 14 and 15 and an integral hook portion 16 parallel thereto. Each of the straps 2, 3, 4 and 5 extends outwardly from the under-side of its fastening element through the eye between the portions 14 and 15 of the same, thence inwardly through the space between the eye and hook portion 16, thence past the inner side of the hook portion 16 through the loop G' of the garter fastener G and back upon itself to the hook portion 16 with which the looped end 2a, 3a, 4a and 5a of each strap is detachably engaged. Thus the fastener element may be slid along the strap for varying the effective length of the same, and the garter fastener may be conveniently assembled by virtue of the detachable connection just described. It is to be noted that in this arrangement the adjustable strap in each instance has direct engagement with the garter fastener.

Not only does the universally elastic lace body 6 serve in the nature of a form for the side hip regions of the wearer's body, with the resulting sense of security upon the part of the wearer, but also this universally elastic body 6 will serve as a means of compensating automatically for and will thus permit the exertion of forces in

different directions along the strip 1 and the garter straps, especially the straps 4 and 5, as well as the strap 7, with the result that, regardless of these different forces in different directions according to the movements of the wearer's body from time to time, there is always ensured a give-and-take action by the universally elastic body 6 and accordingly there is always maintained a firm and snug engagement of the several component parts of the unitary garment with the corresponding parts of the wearer's body and the operation of each of such component parts in the manner intended.

The strap 7 will serve to supplement the front part of the strip 1 as a means for supporting the abdomen of the wearer and will also serve as a binding for the edge of the lace body 6 in co-ordination with the strip 1 and the straps 4 and 5 at the other edges thereof. Also, the particular manner and form of connection between the middle part of the strip 1 and the corresponding part of the strap 7 serves to provide a most natural curved or arched form of supporting means for the abdomen, which is of vital importance in maternity cases because of the attendant sensation of security and comfort and may be realized in the present case. My particular connection for the garter-supporting means eliminates the use of any intermediate loop or the like and thus there is realized a lessening of the cost of manufacture of this garment. Likewise, there may be realized a corresponding saving in cost of manufacture by reason of the fact that my present means of connection for the garter-supporters and for the rear ends of the strip 1 may utilize old forms of fastener elements that may now be procured upon the market, but with the advantages herein pointed out.

What I claim is:

1. A combined abdomen-supporting means and garter belt, comprising a continuous longitudinally elastic strip having a portion adapted to be positioned beneath the abdomen of the wearer so as to serve as a means of support therefor when in position upon her body, said strip having elastic portions extending upwardly and rearwardly from said abdomen-supporting portion so as to be adapted for engagement above the hips of the wearer's body and to have engagement about her waist including her sacroiliac region when in position upon her body said continuous strip being of substantially regular form throughout, a longitudinally elastic garter for each stocking depending in substantially parallel relation to each other from said continuous strip and at the rear-side of the wearer's thigh, a longitudinally elastic garter for each stocking depending from said strip at points along substantially the front median lines of the wearer's thighs and in substantially parallel relation to the other garter for the same stocking in each instance, and a body of universally elastic fabric of substantially triangular form provided only in the region between said continuous strip and the upper end portions of said garters and connected thereto so as to serve as a girdle for the side hip at each side of the wearer's body when in position of use.

2. The same structure as recited in claim 1 hereof and in which said continuous strip has its abdomen-supporting portion of outward curved and upwardly and forwardly inclined form so as to be adapted for effective upward engagement about and beneath the abdomen of the wearer.

3. The same structure as recited in claim 1 hereof and in which said continuous strip has end portions at the rear of the garment provided with means of separable and adjustable engagement between the end portions thereof.

4. In a device of the class described, a releasable fastening means for the straps of wearing apparel, comprising

ing a plurality of duplicate elements each having a closed eye with parallel side portions and a hook portion connected integrally at its one end with one end of said eye and extending in spaced parallel relation to said eye portions and having its other end free, a first strap having its one end provided with a closed loop adapted for readily detachable engagement with the hook portion of one of said elements, a second strap extended from the inner side and thence through the eye of said other element, thence through the space between the inner part of said eye and said hook portion of said other element, thence outwardly through the space between the hook portion and the adjacent portion of the eye of said one of said elements, thence back upon itself and through the eye of said one element and having its end provided with a loop in readily releasable engagement with the hook portion of said other element.

5. In a device of the class described, a garter belt or
the like having a depending strap, a garter-fastener with
20 a strap engageable loop, a fastening element having a
closed eye with parallel side portions and a hook portion
connected integrally with one of said side portions of the
eye and extending in spaced parallel relation thereto and
having its other end free, said strap extending outwardly
25 from the under-side of and through the eye of said fast-
ening element, thence inwardly through the space be-
tween the inner side portion of said eye and said hook
portion, thence past the under-side of said hook portion
and directly outwardly through the loop of the garter-
30 fastener and back upon itself towards the hook portion of
said element, and the end of said strap having an integral
loop in releasable engagement with said hook portion of
said fastening element.

35 6. A combined abdomen-supporting means and garter belt, comprising a longitudinally elastic strip means having a portion adapted to be positioned beneath the abdomen of the wearer so as to serve as a means of support therefor when in position upon her body, said strip means having elastic portions extending upwardly and rearwardly from said abdomen-supporting portion so as to be adapted for engagement above the hips of the wearer's body and about her waist including her sacroiliac region when in position upon her body, said longitudinally elastic strip means being of substantially regular dimension throughout, duplicate bodies of elastic fabric of substantially triangular form with one edge thereof, in each instance, attached along the lower edge of said longitudinally elastic strip means at the sides of the garment so as to cover and snugly engage only the hips of the wearer when in position of use upon her body, and longitudinally elastic garters attached to said triangular bodies so as to extend downwardly therefrom and to ensure snug engagement of said triangular bodies with the wearer's hips when in position of use upon her body.
